UNITED STATES PATENT OFFICE.

LEWIS C. ENGLAND, OF PHILADELPHIA, PENNSYLVANIA.

IMPROVEMENT IN FURNACES.

Specification forming part of Letters Patent No. 154,133, dated August 18, 1874; application filed July 14, 1874.

To all whom it may concern:

Be it known that I, LEWIS C. ENGLAND, of the city of Philadelphia, State of Pennsylvania, have invented an Improved Furnace, of which the following is a specification:

My invention has for its object the saving of fuel and labor in attending a furnace, as well as the successful burning of the smoke and gases, being particularly well adapted to the burning of such fuel as wet spent tan-bark, bituminous coal, &c. It is more economical in the consumption of fuel than any furnace heretofore known to produce heat under steam-boilers and for other useful purposes, being self-feeding and the grates self-cleaning, requiring but little attention after once properly adjusted.

The annexed drawing shows the principle and manner of its construction and operation.

The grates A are an endless chain of cast-iron coned perforated plates, passing over properly-constructed pulleys B B at either end, driven by any suitable device for very slow or faster motion, as occasion may require, and linked together at the ends by small iron plates, and being arranged crosswise of the fire-chamber C. They are cast with as many small holes as can conveniently be made in the pattern to cast from, and a length corresponding to the width of the fire-chamber, and ten to twelve inches wide, with journals at the ends, which pass through the ends of small iron plates, which link them together, thus forming an endless chain of cone-grates. Placed near the center of each shaft, on which the driving-pulleys are placed, is a grooved pulley, over which a common wrought-iron chain passes under the grates, to steady and keep them in place. The hopper or funnel D D is filled with fuel, and should be kept full. One side of the funnel D is formed in part by the outside of the bonnet E and the fire-front F. The other side of the funnel and the hopper may be made of light boiler-iron. The lower portion of the fuel in the funnel will rest on the top and front end of the movable grates A, and, by having passed through the funnel slowly, in contact with the heated bonnet and fire-front, will be heated by the time it is carried by the moving grates into the fire-chamber, so that it will burst into flame immediately. Much if not all of the smoke and gases will be consumed by passing over the hot coals that will be distributed evenly over the surface of the grates, and

through the hot coals and the perforated plate G. No sparks will be developed, the feeding of the fuel is so gentle and regular. Fire-bricks are used for the inside lining of the furnace, and under steam-boilers a number of walls of that material may be constructed and used to retain the heat at the rear end of the furnace. One, H, arched up to the boilers, is placed in front of the rest, directly over the grates, or more than one may be thus employed. There may be a number of diving-flues thus arranged of this material beyond the farther end of the grates, and continued to the farther end of the boilers. The perforated plate G, placed at the rear end of the movable grates, which receives the unconsumed fuel, cinders, &c., is placed on journals at the ends, on the side nearest the grates, and held in place by a crank, and, when requiring cleaning, can be put into a vertical position by a movement of the crank by hand, thus allowing the cinders, &c., to fall into an ash-pit below left for that purpose.

The draft, after passing through the perforated plate G, will enter the flue again at I, passing through the flues to the rear end of the boilers; then, through the return flues or tubes, to the bonnet E, which communicates with the chimney.

The adjustable gate K is made to move up or down, so as to allow more or less of the fuel to enter the fire-chamber.

Near the bottom of the funnel is placed a toothed shaft, L, which is to revolve slowly, and may be geared to move with the grates by the same driving-gear. This will mix and loosen the fuel on the grates.

I claim as my invention—

1. The combination of the smoke-box E, for heating the fuel, with the hopper and funnel D D, substantially as described.
2. The combination of the perforated dumping-plate G with the endless chain-grate, substantially as described.
3. The toothed shaft L, in combination with the funnel D and chain-grate, substantially as described.
4. The adjustable gate K, in combination with the toothed shaft L and funnel D, substantially as described.

LEWIS C. ENGLAND.
